FIG. 7.

Inventor,
By Jacob E. Neahr
R. B. Stickney
Attorney.

UNITED STATES PATENT OFFICE.

JACOB E. NEAHR, OF NEW YORK, N. Y.

COMBINED MATCH SAFE AND IGNITING DEVICE.

Application filed December 26, 1918. Serial No. 268,320.

To all whom it may concern:

Be it known that I, JACOB E. NEAHR, a citizen of the United States, residing in the city, county, and State of New York, have invented certain new and useful Improvements in Combined Match Safes and Igniting Devices, of which the following is a specification.

Certain features of the present invention 10 relate to match-safes combined with match-igniting devices, and are in the nature of improvements over my Patent No. 1,144,612, and my application No. 250,945 (now Patent No. 1,335,012, dated March 30, 1920), 15 in which the matches are struck upon the outer strip of a coil of igniting material, and in which the exposed portion of the strip may be torn off when used up.

One of the features of the present improvements relates to increasing the durability of the strip. The strip, according to the present improvements, is coated with igniting material upon both its outer and inner sides, thereby doubling its life. This 25 improved strip is coiled within the drum, which may generally resemble the drum set forth in said application No. 250,945. The strip is drawn out through an aperture in the wall of the drum, and wound around the drum and secured by a clip. This clip, instead of being set off to one side of the aperture, as in said application, may be arranged to bear upon the strip at both sides of the aperture. Hence, it is rendered convenient to leave exposed either of the faces of the strip when winding the same around the drum; that is, the strip may be wound either to the left or right as it emerges from the aperture, and, in either case, it may be 30 held by the central clip. Hence, after the first exposed face of the outer winding is used up, it may be released from the clip and wound around the drum in the opposite direction, and resecured by the clip, where- 35 by an entirely fresh match-igniting surface is brought into use without withdrawing a new portion of strip from the drum, so that the life of the coil is doubled.

Another feature of the present improvements relates to the cap surmounting the drum which contains the coil. This drum in said application No. 250,945 is held down upon a base by means of an interior connection, which is in the form of a box and 45 serves as a match-safe. This box extends down within the coil and has at its upper

end a cap to catch over the top edge of the drum, and at its lower end a thread whereby it is threaded into the base, thereby drawing down the drum upon the base. In said application, the box and cap are integral, so that it is found to be prohibitive to form this member of gold or other fine metal, owing to the great cost. According to the present improvements, the box portion or 60 body of the match-safe, which is concealed within the drum and pedestal, may be made of inferior metal, while the cap, which surrounds said body and is attached thereto, may be made of fine metal; the cap prefera- 65 bly having an annular enlargement or flange at its lower end to telescope over the top of the box and thereby make the interior wall of the cap flush with the interior of the box or safe.

Another feature of the invention resides in confining the exposed winding of strip more effectively between the flanges which project below and above the same, the lower flange being formed in the drum and the 70 upper flange belonging to the cap. In said application, the clip hinge is supported by the wall of the drum and projects therefrom above the clip and below the cap, thus leaving a clear space above the strip which ex- 75 tends around the drum. One of the objects is to reduce the amount of this clear space and thereby avoid substantial upward displacement of the strip. For this purpose, there is provided a novel bracket or mount 80 for holding the clip. This bracket may be made of a piece of sheet-metal, and may comprise a main portion fastened against the wall within the drum. From the top of this main portion, there is bent out- 85 wardly a leaf, from which are bent downwardly ears to carry the pivot of the clip. This leaf is so thin that it occupies very little space, thereby substantially diminishing the distance between the top of the igniting strip and the bottom of the confining 90 bead of the cap.

In said application, the lower portion of the match box has threads rolled therein to engage a threaded nipple rising from the 105 base, so that, by turning the box around, the cap may be made to bear down upon the drum and force the same downwardly, together with the pedestal, which is thus firmly secured to the base. One of the ob- 110 jects of the present invention is to render the match box suitable for matches of differ-

ent lengths, and to this end an adjustable bottom is provided. This may be in the form of a shallow box, having threads rolled in the side walls thereof, to fit within the 5 threads which (as above explained) are rolled into the bottom of the main portion or body of the match box. This bottom may be rotated to raise or lower the same independently, and thereby accommodate it to 10 matches of different heights.

Other features and advantages will hereinafter appear.

In the accompanying drawings,

Figure 1 is a side elevation, showing novel 15 features of the igniting coil, and the means upon which it is supported.

Figure 2 is a sectional fragmentary elevation to show the preferred form of support for the clip for the igniting coil.

20 Figure 3 is a sectional elevation of parts seen at Figure 1.

Figure 4 is a fragmentary side elevation of parts of the preferred forms of clip mountings seen at Figure 2.

25 Figure 5 is a sectional plan of the match-safe, coil and drum, to illustrate the outer winding of the igniting strip carried around the drum in one direction.

Figure 6 is a perspective view of the preferred form of mounting for the clip for the 30 igniting coil.

Figure 7 is a view similar to Figure 5, but showing the outer winding of strip carried around in the opposite direction from Figure 35 5 to expose the other face thereof for use.

Figure 8 is a perspective view of a novel match-igniting coil, constituting a separate article of manufacture.

A match-igniting coil 10 has igniting material 11 entirely covering one side or surface thereof, and igniting material 12 entirely coating the other side thereof, Figure 40 8. This coil may be placed within a drum 13, which may correspond substantially with the drum disclosed in said application No. 250,945, and may have an aperture 13^a through which the strip 10 may be paid out. A clip to hold the tip of the exposed winding of strip may consist of a pair of legs 50 14, pivoted at their upper ends at 15 within ears 16 provided upon the exterior of the drum; and they may carry at their lower ends a roller 17 to spring under a bead 18 at the bottom edge or floor of the drum 13.

55 At Figure 5, the strip is shown as brought out through said aperture 13^a and carried to the left entirely around the drum far enough to overlap said aperture, where it is clipped by the members 14. After the exposed surface of the strip becomes worn off, the clip may be released and this outer winding may be loosened and carried around in reverse direction, as at Figure 7, and re-engaged by the clip, thus doubling the life 60 65 of this winding. After both sides have thus

been used, a fresh portion of the strip may be pulled out through the opening 13^a and wound in either direction around the drum and subsequently reversed, and so on.

Said drum 13 surmounts a cylindrical pedestal 19, which may be integral with the bead 18 and drum 13, and may rest upon a seat 20 formed upon a base 21. This drum is held down upon the base by means of an interior hollow device 22, which constitutes a 70 75 match box arranged within the coil 10 of match-igniting strip and extending down into the pedestal 19. This match box has an annular cap 23 to rest upon the top edge of the drum 13; and in the bottom of the match box are rolled threads 24, to fit threads in a nipple 25 which rises from the base 21 within the pedestal 19; so that, by turning the match box around, the cap 23 is caused to serve as a clamp, for forcing the drum and pedestal down firmly upon the base 21.

The main portion of the match box 22 comprises a hollow cylinder, upon which is closely fitted an interior flange or brim 26 formed upon the cap 23; said brim at its lower edge being enlarged at 27 to telescope or fit tightly over the top of the box 22, and preferably riveted thereto as at 28; the interior of the brim 26 being flush with the interior of the match box 22, so as to form practically an upper portion of the box. The cap 23, 26 may be of gold, silver, or other fine metal while the body 22 of the box may be of steel or other inexpensive metal.

The match box 22 may be a cylinder open 100 at its lower end, and may be provided with an adjustable bottom in the form of a shallow box or cup, comprising a floor 29 and a cylindrical side wall 30, which has rolled threads at 31 to fit the inner faces of the threads 24 rolled in the match box 22. This device 29, 30 may be rotated up and down to vary the position of the floor 29, and thereby accommodate matches of different lengths. There may be pressed in the bottom of the box a transverse nick 32, to accommodate a screw-driver which may be inserted from the top of the device to raise or lower the floor.

At Figure 6 is shown a novel mounting 115 for the clip which holds the igniting strip, said mounting or bracket comprising a pair of vertical inner plates 33, one upon each side of the egress opening 13^a, so that the strip can be led out between said plates. These plates 120 are bent downwardly from a horizontal leaf 34, from the outer end of which depend ears 35, to which are pivoted at 36 the legs 14 of the clip, as at Figure 4. It will be seen at Figures 2 and 4 that the clearance between 125 the top of the strip 10, and the bead 37 formed upon the cap 23, is so slight as to be negligible; while the clip is, nevertheless, firmly supported because of the substantial width of the leaf 34.

The base 21 of the match-safe is hollowed or dished out, and has an exterior rim 38.

Variations may be resorted to within the scope of the invention, and portions of the 5 improvements may be used without others.

Having thus described my invention, I claim:

1. The combination of a drum for containing a coil of match-igniting strip, a 10 match box extending down within the drum and coil, and a base, said match box having an annular ornamental cap to bear down on said drum, and having at its lower end a threaded connection with said base to hold 15 the drum down upon the base, said cap being of more precious metal than the box and attached to the top thereof.
2. The combination of a drum for containing a coil of match-igniting strip, a 20 match box extending down within the drum and coil, and a base, said match box having an annular ornamental cap to bear down on said drum, and having at its lower end a threaded connection with said base to hold 25 the drum down upon the base, said cap being of more precious metal than the box and attached to the top thereof, the cap having an interior brim or flange which fits over the top of the match box.
3. The combination of a drum for containing a coil of match-igniting strip, a 30 match box extending down within the drum and coil, and a base, said match box having an annular ornamental cap to bear down 35 on said drum, and having at its lower end a threaded connection with said base to hold the drum down upon the base, said cap being of more precious metal than the box and attached to the top thereof, the cap 40 having an interior brim or flange which fits over the top of the match box, the wall of the brim or flange being flush with the wall of the match box.

4. In combination, a drum to contain a coil of match-igniting strip, a box inserted 45 within said drum and having an annular cap to bear down upon the drum, the body of said box being in the form of a shell open at its bottom, threads rolled into the bottom of said shell, a base engaged by said 50 threads for enabling the cap to hold the drum down upon the base, and an adjustable floor having threads to engage the threads in said shell.

5. In combination, a drum to contain a 55 coil of match-igniting strip, a box inserted within said drum and having an annular cap to bear down upon the drum, the body of said box being a shell open at its bottom, threads rolled into the bottom of said 60 shell, a base engaged by said threads for enabling the cap to hold the drum down upon the base, and an adjustable floor in the form of a shallow box having threads rolled in its sides to engage the inner surfaces of the threads in said box, whereby the 65 floor may be screwed up or down.

6. The combination of a drum to contain a coil of ignition strip, and a clip pivoted thereon for retaining an outer winding of 70 the strip, said drum having upper and lower flanges to confine the strip against edgewise displacement, and said clip being pivoted upon a mounting which comprises a thin leaf projecting from the drum between the strip and the upper flange, a plate being bent down from the inner end of said leaf and fastened against the interior surface of the drum, and ears bent down from the outer portion of said leaf to carry the 75 pivot of said clip.

JACOB E. NEAHR.
